UNITED STATES PATENT OFFICE

ALFRED GRIEB, OF ELIZABETH, NEW JERSEY, ASSIGNOR TO THE SINGER MANUFACTURING COMPANY, OF ELIZABETH, NEW JERSEY, A CORPORATION OF NEW JERSEY

NEEDLE-CLAMP FOR SEWING MACHINES

Application filed April 24, 1931. Serial No. 532,440.

This invention relates to devices for clamping the needle of a sewing machine in working position relative to the needle-bar and has for an object to provide a needle-clamp which is simple in construction, inexpensive to manufacture and easy to assemble, and which will securely clamp the needle yet permit the latter to be readily removed when desired.

- 10 A further object of the invention is to provide a simple and effective needle-clamp, the set-screw element of which is disposed, as usual, on the right-hand side of the needle-bar, which needle-clamp will locate and 15 secure the needle in proper working position for such needle to be threaded from right to left or, in other words, with the long grooved side of the needle-blade toward the set-screw and the short grooved side of the needle- 20 blade away from the set-screw.

The invention comprises the devices, combinations and arrangements of parts herein-after described and claimed.

The features of the invention and the advantages attained thereby will be readily understood by those skilled in the art by the following detailed description of a preferred embodiment of the invention illustrated in the accompanying drawing, in 25 which Fig. 1 is a front side elevation of the lower end-portion of the needle-bar and the needle-bar housing head of the sewing machine, with the needle-clamp carried by the needle-bar. Fig. 2 is a vertical section 30 through the device. Fig. 3 is a section on the line 3—3 of Fig. 2. Fig. 4 is a section of the band element only of the needle-clamp on the line 3—3 of Fig. 2. Fig. 5 is a sectional view of the needle-bar only, on the line 35 3—3 of Fig. 2. Fig. 6 is a perspective view 40 of the needle-clamping gib. Fig. 7 is an elevation or outer face view of the gib as applied to the needle-bar. Fig. 8 is a side elevation of the lower end-portion of the needle- 45 bar. Fig. 9 is a front elevation, partly in section, of the lower end portion of the needle-bar. Fig. 10 is a sectional view similar to Fig. 2 showing the parts displaced from 50 operative position in the process of disassembling the device. Fig. 11 is a perspec-

tive view of the sewing machine needle shown in Figs. 1, 2 and 3.

1 represents the lower portion of the needle-bar housing head of the sewing machine which is formed as usual at the free end 55 of the sewing machine gooseneck. Mounted in the head 1 is the reciprocating needle-bar 2 of cylindrical form having in its lower end a needle-shank-receiving recess 3 in the form 60 of a groove milled in one side of the needle-bar. The groove 3 has parallel side walls 3', Figs. 5 and 8, and a flat bottom wall 3''. The groove 3 is of a width sufficient to receive the shank 4 of the needle 5 with the 65 slabbed face 6 of the needle-shank 4 in flatwise engagement with the bottom wall 3'' of the groove 3. A stop-pin 7 is positioned in the groove 3 to properly locate the upper end of the needle relative to the needle-bar.

Embracing the recessed lower end of the 70 needle-bar 2 is the clamping band 8 having a lateral screw-threaded aperture receiving the set-screw 9. The proximate surfaces of the needle-bar 2 and clamping band 8 are formed with coaxial opposed cylindrical 75 apertures 10 and 11 which receive the enlarged cylindrical head 12 of the needle-clamping gib 13, the lower end-portion 14 of which extends below the lower end of the needle-bar 2 and is bent to the form of a 80 thread-guiding hook. The enlarged head 12 of the gib is adapted to be engaged by the inner end of the set-screw 9, as shown in Figs. 2 and 3, and forced against the shank 4 of the needle 5, thereby clamping the latter securely 85 in position in the recess or groove 3. Since the enlarged head 12 of the gib is partially received in each of the transverse coaxial recesses 10 and 11 of the needle-bar 2 and clamping band 8, respectively, it serves to 90 lock these two parts together and to prevent relative displacement of such parts from their respective operative positions.

The lower end-portion of the needle-bar 2 is slabbed off or cut away at 15 to clear the enlarged head 12 of the gib when the latter is shifted as far as possible into the recess 11 in the clamping band 8. The gib and clamping band may thus be unlocked and removed 95 from the needle-bar 2, as shown in Fig. 10. 100

This unlocking of the parts may be effected by loosening the set-screw 9 and by engaging the exposed lower end-portion 14 of the gib and shifting the gib toward the set-screw 9 to disengage it from the aperture 10. The gib 13 serves to distribute the pressure of the set-screw 9 over a considerable portion of the length of the needle-shank 4 and effects a more secure grip of the needle than would 10 be effected by the end of the set-screw only, were the latter allowed to directly engage the needle-shank. The side-wall portions of the recesses 10 and 11 which cooperate with the enlarged head 12 of the gib to prevent 15 movement of the band 8 lengthwise of the needle-bar, may be described as upper and lower locking-wall-portions. It is not essential that the head 12 of the gib be cylindrical or that the recesses 10 and 11 be circular, as 20 the desired locking-wall-portions may obviously be provided with various shapes.

It is the standard practice to provide a long groove 5' on one side of the blade of a sewing machine needle and a short groove 5" on the 25 opposite side adjacent the eye 5°. These grooves are thread-clearance grooves. The sewing machine loop-taker always takes the needle-loop from the short-grooved side of the needle. To insure precision in the location 30 of the needle relative to the loop-taker, it is the practice to slab the shank of the needle on the short-grooved side of the latter, as indicated by the numeral 6. The slabbed side 6 of the needle shank is clamped 35 against a seat fixed on the needle-bar. With needles of various sizes a fixed relation or spacing is maintained between the plane of the slabbed face of the needle shank and a parallel plane tangent to the short grooved 40 side of the needle-blade, so that a standard clearance is provided between the sewing machine loop-taker and the needle-blade for all sizes of needles.

Various sewing machine attachments, such 45 as ruffling and buttonholing attachments, are provided with operating levers having forked ends adapted to embrace the usual needle-clamp set-screw at the right hand side of the needle-bar. The position of such set-screw 50 should, therefore, not be disturbed.

The present improvement provides for the secure clamping of the standard sewing machine needle in a position reversed from its usual position, for cooperation with a loop-taker having a beak passing to the left of the needle-blade, without disturbing any of the conditions or relations above referred to.

Having thus set forth the nature of the invention, what I claim herein is:—

60 1. A sewing machine needle-clamp comprising, a needle-bar formed in one end with a needle-shank-receiving recess, a clamping band embracing the recessed end of the needle-bar, said needle-bar and clamping band 65 having in their proximate surfaces opposed

gib-receiving apertures, means for locking said band against movement endwise of the needle-bar comprising a gib seated in said opposed apertures, and a clamp-screw carried by said band and adapted to engage said gib and force the latter into clamping engagement with the shank of a needle seated in said needle-shank-receiving recess, said gib being movable out of the gib-receiving aperture in the needle-bar to unlock said band for removal from the needle-bar.

2. A sewing machine needle-clamp comprising, a needle-bar formed in one end with a needle-shank-receiving recess, a clamping band embracing the recessed end of the needle-bar, said needle-bar and clamping band having in their proximate surfaces opposed apertures transverse to the longitudinal axis of the needle-bar, the transverse aperture in the needle-bar being in communication with said needle-shank-receiving recess, a locking gib seated in said opposed apertures, and a clamp-screw carried by said band in position to engage said gib, said gib being movable out of the gib-receiving aperture in the needle-bar to unlock said band for removal from the needle-bar.

3. A sewing machine needle-clamp comprising, a needle-bar formed in one end with a needle-shank-receiving recess, a clamping band embracing the recessed end of the needle-bar, said needle-bar and clamping band having in their proximate surface-portions opposed gib-receiving recesses defining upper and lower locking-wall-portions, a locking gib in said recesses in engagement with said locking-wall-portions, and a set-screw separate from said gib and carried by said band and adapted to engage said gib, the recess in said clamping band being deep enough to permit withdrawal of said locking gib from the opposed recess in the needle-bar.

4. The combination with a needle-bar formed at one end with a longitudinal needle-shank-receiving groove open at the side of the needle-bar throughout the length of said groove and having an enlarged portion spaced from the end of the needle-bar, of a needle-clamping gib received in said groove and having an enlarged head partially received in the enlarged portion of said groove, a clamping band embracing said needle-bar and having an inner recess receiving a portion of said enlarged head, and a set-screw carried by said band in position to bear upon said gib, the head of said gib being movable out of the enlarged portion of said groove in a direction transverse to the longitudinal axis of the needle-bar to unlock said clamping band for removal from the needle-bar.

5. A needle-clamp for sewing machines comprising, a needle-bar formed at one end with a needle-shank-receiving groove widened at one point to form a cylindrical recess

the axis of which is transverse to the axis of the needle-bar, a clamping band embracing the grooved end of the needle-bar and formed with an inner cylindrical recess coaxial with said first-mentioned cylindrical recess, a cylindrical gib disposed in said recesses, a set-screw carried by said clamping band and adapted to engage said gib, said gib having a shank-portion extending longitudinally of the needle-bar and beyond the end of the latter.

6. A needle-clamp for sewing machines comprising a needle-bar formed at one end with a needle-shank-receiving groove widened at one point to form a cylindrical recess the axis of which is transverse to the axis of the needle-bar, a clamping band embracing the grooved end of the needle-bar and formed with an inner cylindrical recess coaxial with said first-mentioned cylindrical recess, a cylindrical gib disposed in said recesses, a set-screw carried by said clamping band and adapted to engage said gib, said gib having a shank-portion extending longitudinally of the needle-bar and beyond the end of the latter, said shank portion having a hooked extremity constituting a needle-thread guide.

In testimony whereof I have signed my name to this specification.

ALFRED GRIEB.
